UNITED STATES PATENT OFFICE.

BESSIE H. MERRIHEW, OF CLEVELAND, OHIO.

BRUSH.

Application filed May 31, 1923. Serial No. 642,499.

To all whom it may concern:

Be it known that I, BESSIE H. MERRIHEW, a citizen of the United States, residing at Cleveland, in the county of Cuyahoga and 5 State of Ohio, have invented a certain new and useful Improvement in Brushes, of which the following is a full, clear, and exact description.

This invention relates to scrubbing 10 brushes, and while of quite general application for washing and scrubbing operations, it is especially useful for washing dishes.

An object of the present invention is to 15 provide a scrubbing brush formed by a pair of looped bristle brushes so formed and secured together that they will retain a cake of soap between them without any additional holding means.

20 A further object is to provide a scrubbing brush which has a relatively large scrubbing surface and which can be readily inserted in cups, pitchers, tumblers, jars, pots and other dishes and cooking utensils.

25 A further object is to provide a scrubbing brush which has parts provided with bristles of different stiffness so that the scouring and washing action is facilitated.

30 A further object is to provide a two-part soap retaining brush which is so connected to the handle that the parts of the brush may be separated when desired for the purpose of cleaning them.

The following description and accompanying drawings set forth in detail certain 35 means embodying the invention, the disclosed means, however, constituting but one of the various mechanical forms in which the principle of the invention may be employed.

40 Reference should be had to the accompanying drawings forming a part of this specification in which Fig. 1 is a longitudinal sectional view showing the brushes and the means for attaching the brushes to the handle; Fig. 2 is a side elevation of the 45 brushes; Fig. 3 is a front elevation of the brushes; Fig. 4 is a transverse section through the brushes.

50 Referring to the accompanying drawings, the scrubbing brush consists of a large brush 1 and a smaller brush 2. The brushes 1 and 2 are both looped twisted-in-wire bristle brushes and are so mounted that the side face of the smaller brush lies against the 55 side face of the larger brush. The large brush 1 has an elongated loop of twisted

wire 3 in which the radially extending bristles 4 are secured. The sides of the loop 3 are substantially parallel and the bristles 4 are of such length that the bristles extending from opposite sides of the loop overlap at the center of the brush. The smaller brush 2 has a twisted wire loop 5 which has substantially the same shape as the loop 3 of the larger brush but is of less width and length. The loop 5 has radially extending bristles 6 secured between the strands thereof which are considerably shorter than the bristles of the larger brush. The brushes 1 and 2 are secured to a suitable handle 7 in such a manner that the small brush is held tightly in engagement with the larger brush, the brushes, however, may be sprung apart sufficiently at their outer ends to permit a cake of soap such as indicated by the numeral 8 in Figs. 2 and 4 to be inserted between them. The space between the sides of the wire loop 5 of the smaller brush is so narrow that the cake of soap cannot be pushed through this loop. The engagement between the bristles of the small brush and the bristles of the large brush prevents the small brush being pushed far enough toward the large brush to force the soap out through the loop of the larger brush. The handle 7 is made long enough so that dishes may be washed without putting the hands in the water. The present device enables dishes to be conveniently washed in running water which may be hotter than could be used where it is necessary to put the hands in the water. The cake of soap retained between the brushes will furnish sufficient suds for thoroughly cleaning the dishes so that the dishes may be washed

90 in soapy water and rinsed in the same operation. As the soap becomes softened by the hot water the bristles of the brushes will imbed themselves in the soap so that the soap will be securely retained between the brushes until it is all dissolved. In the use 95 of the brush the surface being cleaned will be engaged alternately by the short relatively stiff bristles of the small brush and the longer more flexible bristles of the large brush so that the particles adhering to the articles being washed may be easily loosened and washed off.

The handle 70 is provided with a longitudinal bore 9 which extends through the greater portion of its length and receives the shank of the brush which is formed by

extensions of the wire forming the loops of the brushes 1 and 2. At its open end the handle is provided with a suitable ferrule 10 which has an opening through which the shank of the brush extends. The loops of the two brushes as well as the attaching shank are preferably formed of one length of twisted wire. The portion of the wire forming the loop of the larger brush has one end extending down into the handle and from the opposite end a loop 11 extends into the handle. The loop of the smaller brush is an extension of the loop 11, the wire being bent back upon itself to form the loop 5 and extending back into the handle. In addition to the loop 11 within the handle there are the two free end portions 12 and 13 of the wire which are bent at their ends to form hook portions 14 and 15 which bear with spring pressure against the wall of the bore 9 and serve to yieldingly hold the shank in adjusted position within the handle. A cross-pin 16 extends through the bore adjacent the outer end thereof through the loop 11 and between the wire ends 12 and 13. When the brushes are secured in the position shown in the drawing, the small brush 2 is held tightly against the larger brush 1. Whenever it is desired to clean the brushes, i. e., to remove accumulations of dirt from between the brushes, the brushes may be pulled outwardly until the end of the loop 11 engages the cross-pin 16 in which position the brushes may be readily spread apart to permit the cleaning of the inner sides thereof.

Having described my invention, I claim.

1. A device of the character described, comprising a handle, and a pair of bristle brushes secured to the handle, each of said brushes having a core in the form of a loop with bristles radiating from the core and surrounding the same substantially throughout the length of the loop, said brushes being held in face to face engagement with each other with their loops side by side, one of said brushes being smaller than the other and positioned centrally with respect to the larger brush.

2. A device of the character described, comprising a handle, and a pair of bristle brushes secured to the handle, each of said brushes having a core in the form of a loop with bristles radiating from the core and surrounding the same substantially throughout the length of the loop, said brushes being held in face to face engagement with each other with their loops side by side, one of said brushes being smaller than the other and having shorter bristles said smaller brush being positioned centrally with respect to the larger brush.

3. A device of the character described,

comprising a handle, and a pair of bristle brushes of similar shape secured to the handle, each of said brushes having a core in the form of a loop with bristles radiating from the core and surrounding the same substantially throughout the length of the loop, said brushes being yieldingly held in face to face engagement with each other with their loops side by side, one of said brushes being smaller than the other and positioned centrally with respect to the larger brush, said larger brush having the bristles which extend inwardly from one side of the loop engaging the bristles which extend inwardly from the opposite side of the loop.

4. A device of the character described comprising a hollow handle having an opening in one end, and a pair of bristle brushes each having a bristle carrying core in the form of a loop the cores forming the loops to which the bristles are attached being extended to provide means for attaching the brushes to the handle, at least one of the brushes having an elongated extension slideable within the handle so that the brushes may be separated to permit cleaning thereof, means for yieldingly holding the slideable extension in adjusted position within the handle, and means for limiting the outward movement thereof.

5. A device of the character described comprising a handle with a longitudinal bore extending from one end thereof, and a pair of bristle brushes each having a bristle carrying core in the form of a loop the cores forming the loops to which the bristles are attached being extended to provide an elongated shank slideably mounted within the bore of the handle so that the brushes may be pulled outwardly from the end of the handle and separated to permit cleaning thereof, and means for limiting the outward movement of the shank and for yieldingly holding the shank in its innermost position in the handle.

6. A device of the character described comprising a handle, and a pair of brushes mounted on the handle, each of said brushes having a core in the form of a loop with bristles radiating from the core and surrounding the same substantially throughout the length of the loop, said brushes being held in face to face engagement with each other, the loop of one of said brushes being narrower than the loop of the other and positioned centrally with respect to the larger loop, the space between the sides of the loop of each core being closed by overlapping bristles extending from opposite sides of the loop.

In testimony whereof, I hereunto affix my signature.

BESSIE H. MERRIHEW.
